REGENERATIVE COKE OVEN WITH VERTI-
CAL HEATING FLUES

Josef Schaefer, Dortmund, Germany

Application August 11, 1930, Serial No. 474,486
In Germany September 20, 1929

1 Claim. (Cl. 202—135)

The invention relates to regenerative coke ovens having vertical heating flues and lower and upper burning places therein which are alternately fed with fuel, and header passages 5 provided in the heating walls and connected to the regenerators. In the operation of regenerative coke ovens generally additional fresh air of combustion is supplied to the heating flues at a certain distance above their floor 10 through small passages provided in the header bricks of the heating walls. Now the invention has for its object to supply, with regenerative coke ovens of the above type, fuel components preheated by regeneration to the heating flues 15 between the upper and lower burning places through header passages. To this end each two header passages which open into the heating flues at a certain distance from the upper and lower burning places, are connected to different regenerators, so that in the one direction 20 of draft the fuel component is supplied additionally to the same flue by the one header passage and in the other direction of draft by the other header passage. This arrangement may further 25 be modified in that these two header passages may open into the flue at different levels, so that in the one direction of draft the one header passage supplies fuel component at a different level from that at which fuel is supplied by the 30 other header passage during the draft in the other direction. Furthermore, one of these two header passages only may open into the flue at a certain distance from the upper and lower burning places but this passage is connected 35 alternately to two regenerators in such a manner that it additionally supplies fuel component preheated by regeneration to the same flue or flues in both directions of draft.

In order that the invention can be more 40 readily understood, three embodiments of the same are illustrated by way of example in the drawings which accompany and form part of this specification. In the drawings

Figure 1 is a fragmentary longitudinal section 45 through a heating wall of a combined regenerative coke oven forming the first embodiment of the invention,

Figure 2 is a corresponding cross section through a battery of ovens,

Figure 3 is a fragmentary horizontal section 50 through the heating flues on line A—B of Figure 1,

Figure 4 illustrates a second embodiment of the invention by a sectional view similar to Figure 1,

Figure 5 is a corresponding cross section similar to Figure 2,

Figure 6 is a corresponding horizontal section similar to Figure 3,

Figure 7 illustrates by a sectional view similar to Figure 1 a third embodiment,

Figure 8 is a corresponding cross section similar to Figure 2, and

Figure 9 is a corresponding horizontal section similar to Figure 3.

In the combined regenerative coke oven illustrated in Figures 1 to 3 header passages i^1 and i^2 are provided in the header bricks of the heating walls in the manner usual with coke ovens having alternately fed upper and lower burning 70 places, which header passages when the oven is heated by strong gas supply air of combustion to the upper burning places in the one direction of draft and in the other direction they lead off the waste gases from the heating flues h . When 75 the oven is heated by weak gas, in the one direction of draft the passages i^1 supply air of combustion and the passages i^2 weak gas to the upper burning places, while in the other direction of draft all passages i^1 and i^2 draw off the 80 waste gases from the flues h . This arrangement is already known.

Now according to the invention small passages j^1 are branched off from the header passages i^1 on their upper portion which passages j^1 85 open into the two adjacent heating flues h . The header bricks including the passages i^1 have further provided in them each a narrower header passage i^2 from which small passages j^2 are branched off which open into the two adjacent 90 heating flues below the small passages j^1 issuing from the header passages i^1 . The passages i^1 are connected at bottom to the air regenerators r^2 while the passages i^2 communicate at bottom with the air regenerators r^1 to which 95 are also connected the heating flues h at bottom. The header passages i^2 are connected at bottom to the gas regenerators r^2 while the heating flues h are connected at bottom to the gas regenerators r^1 , as best to be seen from Figure 2. 100

When heated by weak gas this oven operates as follows.

In the one direction of draft preheated air of combustion is fed to the flues h at bottom from the regenerators r^1 while preheated weak gas is 105 supplied from the regenerators r^2 . Besides, additional preheated air of combustion enters the flues h through the branch passages j^3 from the regenerator r^1 ; the waste gases escape through the header passages i^1 and i^2 to the regenerators 110

r^2 and f^2 . After reversal of draft preheated air of combustion from the regenerators f^2 is fed to the flues h on top through the header passages i^1 and preheated weak gas from the regenerators 5 r^2 through the header passages i^2 . Besides, additional preheated air of combustion enters below the upper burning places from the header passages i^1 through the branch passages j^1 . The waste gases escape from the flues h through the 10 regenerators r^1 and f^1 .

With strong gas heating, in the one direction of draft preheated air of combustion is fed to the flues h at bottom from the regenerators r^1 and f^1 and somewhat above also through the 15 header passages i^3 . The strong gas enters the flues h through strong gas ducts b^1 while the waste gases escape through the header passages i^1 and i^2 to the regenerators f^2 and r^2 . After reversal of draft the preheated air of 20 combustion enters the flues at top from the regenerators f^2 and r^2 through the header passages i^1 and i^2 and additional air of combustion is supplied further somewhat below through the branch passages j^1 . The strong gas is fed to the 25 flues at top through ducts b^2 , while the waste gases escape at bottom to the regenerators r^1 and f^1 .

With ovens that are heated merely by strong gas, as illustrated in Figures 4 to 6, the header 30 passages i^3 are dispensed with, but in this case the header passages i^2 must have branch passages j^2 opening into the two neighboring heating flues h , which branch passages j^2 are disposed between the upper and lower burning places at 35 another level than the branch passages j^1 . Furthermore, the heating flues h at bottom and the header passages i^1 which in this case extend only up to the branch passages j^1 , are connected to the one group of regenerators f and the flues h . 40 are further connected through the header passages i^2 at top to the other group of regenerators r , so that in the one direction of draft preheated air of combustion from the regenerators f is fed both to the lower burning places at bottom 45 and somewhat above through the branch passages j^1 , while the waste gases escape through the header passages i^2 to the regenerators r . After reversal of draft, preheated air of combustion is fed from the regenerators r to the 50 flues h both at top through the header passages i^2 and somewhat below through the branches j^2 . The waste gases escape from the flues h at bottom to the regenerators f .

In these embodiments of the oven, and this in 55 both combined and strong gas heated ovens, a small portion of the waste gases can escape from the flues h through the branch passages j^1 or j^3 , and with the strong gas heated oven through the passages j^2 branched off in this case from 60 the header passages i^2 , this escapement taking place during that direction of draft in which the regenerator connected to the header passages in question is sucking off waste gases. By arranging the described branches of the header 65

passages at different levels relatively to one another the quantity of the waste gases thus prematurely sucked off can be reduced adequately. This drawback, although rather trifling, can however be entirely eliminated by 80 connecting for instance the header passages i^7 , see Figures 7 to 9, which in this case are advantageously united to pairs, both to the air regenerators f^1 and to the regenerators f^2 and by 85 providing throttling valves a^1 and a^2 to be operated alternately, in the passages that connect the regenerators to the header passages i^7 , by means of which valves the latter can be shut off from that of the two regenerators f^1 , f^2 , which is just sucking off waste gases and be 90 connected to that just feeding fresh air of combustion. In this case additional fresh air of combustion is thus permanently supplied alternately through the header passages i^7 from one of the two regenerators f^1 , f^2 so that the above 95 branches issuing from the passages i^1 are superfluous, as illustrated in Figure 7. As further to be seen from Figures 7 and 8 several passages i^7 can be provided superposedly. As for the rest the arrangement and mode of operation of 100 this oven is the same as that of the preceding embodiment.

Furthermore, the header passages i^7 can be connected to a special pair of regenerators that means to regenerators which alternately supply 105 fresh air of combustion to the header passages i^7 independently upon those regenerators which communicate with the passages i^1 , which regenerator further can be heated up alternately by a portion of the waste gases that escape from 110 the heating flues.

It may still be noted that, as a matter of course, also additional heating gas instead of air of combustion can be supplied to the heating flues in a similar manner that means 115 through additional header passages.

I claim:

A regenerative coke furnace having a coking chamber and a hollow heating wall therefor, said heating wall having a plurality of transverse walls dividing the space within the heating wall into a plurality of vertical combustion flues, each of said flues having burners therein at the top and bottom thereof and means to supply gas to said burners, a plurality of air 120 regenerators, said transverse walls having passages therein, at least two passages communicating with each combustion flue, one of the passages connected to any combustion flue communicating with said combustion flue at a point 125 intermediate its length and spaced from the ends thereof, means to connect said first passage interchangeably to either of two air regenerators, and another of said passages independent of the first passage connected to the 130 same combustion flue communicating with the flue near its top and being connected to a regenerator.

JOSEF SCHAEFER.
